UNITED STATES PATENT OFFICE.

LEON G. MYERS, OF CLINTON, ILLINOIS.

AIR-CIRCULATING ATTACHMENT FOR HOT-AIR FURNACES.

Application filed July 12, 1924. Serial No. 725,606.

To all whom it may concern:

Be it known that I, LEON G. MYERS, a citizen of the United States, a resident of Clinton, in the county of De Witt and State of Illinois, have invented new and useful Improvements in Air-Circulating Attachments for Hot-Air Furnaces, of which the following is a specification.

This invention has reference to an air circulating attachment for hot-air furnaces, and it has for its principal object to provide for a more rapid circulation of air in houses or buildings heated by such furnaces; to freshen and change the air more often, and to provide for introducing the incoming air into the furnace into direct contact with the wall of the fire-pot and in an even stream, the result of which will cause the rest of the air in the furnace to rise upward and toward the fire-pot, thus creating a partial vacuum which is filled by air rushing down the cold air pipe.

The invention has for a further object an attachment of the character referred to which includes a blower and air circulating units between the blower and outside wall of the fire-pot of a hot-air furnace, each arranged to deliver in uniform streams the air from the cold air duct or ducts and being heated by coming into contact with the heated wall of said fire-pot immediately sets up an increased circulation of the air and accelerates the flow of the rest of the air in the furnace, the result of which is to freshen or change the air in the rooms to be heated more rapidly than heretofore.

That the invention may be more fully understood reference is had to the accompanying drawings forming a part of the description, illustrating a preferred embodiment of the invention, in which:

Figure 1 is a view showing a hot-air furnace and my air circulating attachment with a blower associated therewith;

Figure 2 is a horizontal section on the line 2—2 Figure 1, showing my air circulating attachment associated therewith;

Figure 3 is a perspective view of the head unit or separating chamber, as the same would appear on the line 3—3 Figure 1, and

Figure 4 is a cross-section through one of the air conducting ducts, at 4—4 Figure 1.

Like characters of reference denote corresponding parts throughout the figures.

Referring to the furnace, which may be of any of the well known types of hot-air fur-

naces, A designates the fire-pot associated with other necessary units which need not be here described, all incased within the usual sheet-iron casing B, and supplying air to the chamber surrounding the fire-pot and furnace parts proper within the casing B, is the usual cold air intake pipe C. Such a pipe ordinarily introduces the cold air to be heated by the furnace, within the casing B and is heated by the heat radiating from the wall of the fire-pot and associated parts and such heated air is taken off or conducted to the rooms of a dwelling through hot-air pipes D.

My air circulating attachment is interposed in the cold air intake pipe C and by means of a blower forces the sucked-in-air in an even or balanced stream directly into contact with the base of the fire-pot A and in an upward direction. Such an attachment preferably includes a head unit or separating chamber 1 divided into a plurality of air conducting passage-ways a, b, b', c and c' which are of equal area. Connected to said head unit 1 and communicating with the air passage-way a to receive and conduct air therefrom, is a conducting unit 2 provided with a discharging vent 3 preferably located directly in the rear of the furnace, see Figure 2 with the discharge opening of the vent 3 immediately adjacent the wall of the fire-pot A.

Connected to the head unit 1 and communicating with the air passage-ways b and b', respectively to receive and conduct air therefrom, are conducting units 4 and 5, which extend, respectively, around and to the left and right sides of the furnace, see Figure 2, each having a discharging vent 6, 95 extending part way around the fire-pot A from the vent 3 of unit 1, with the discharge openings of said vents 6 immediately adjacent the wall of the fire-pot A.

Connected to the head unit 1 and communicating with the air passage-ways c and c', respectively to receive and conduct air therefrom, are conducting units 7 and 8 which extend, respectively, around and to the left and right sides of the furnace, see Figure 2, each having a discharging vent 9 extending along the forward sides of the fire-pot A from the vents 6 of the units 4 and 5, with the discharge openings of said vents 9 immediately adjacent the wall of the fire-pot A. I prefer to provide the units 4, 5, 7 and 8 with similar dividing or deflecting

partitions 10, preferably located mediate the ends of their respective vents so as to direct the air discharged against the surface of the fire-pot in an even or balanced stream thereagainst. As shown in the drawings, the several units 2, 4, 5, 7 and 8 are conducting pipes to the discharge ends of which are connected the respective vents. These vents are each, somewhat of the form shown in cross-section in Figure 4, i. e., extend upwardly and have contracted mouths which lie next adjacent the base of the fire-pot and discharge the air in an upward direction against the wall of the fire-pot and over a considerable area thereof.

11 designates an electric blower, of any well known make, to which is connected the inner end of the air intake pipe C, and to which is also connected the intake end of the head unit 1. I prefer to connect the head unit 1 with the blower 11 by a preferably canvas sleeve 12 or other universal connection for the purpose of removing all vibration. As will be understood the blower 20 sucks in the cold air through the cold air intake pipe C and any vents connected thereto and forces such cold air into and through the head unit 1 and ducts connected thereto. Such suction will cause a speeding up of the 25 down draft in the vents connected with said cold air intake pipe C. When the air forced into the unit 1 reaches the separating partitions therein, such air is equally divided and directed through the passage-ways a, b, b', c and c' and thence to and 30 discharged in an even or balanced stream against the wall of the fire-pot through the several vents 3, 6 and 9.

The respective units of the attachment 40 will discharge a constant stream of cold air against the hottest part of the furnace, and as a result will cause the rest of the air within the casing B to rise upward and toward the fire-pot or its superimposed structure, thus creating a partial vacuum which is filled by air rushing down the cold air pipes or vents. The use of the attachment 45 has demonstrated that a more rapid circulation of the air is obtained and in so doing insures a constant change of air inside a dwelling and a reheating with each passing through the furnace.

The attachment is preferably supported in proper position by a strip or strap of iron 55 13 conforming to the shape of that part of the furnace against which the attachment is placed, and supported by legs 14.

By adjusting the registers the amount of 60 return air to any room can be increased or decreased. Comfort is assured and coal economy is realized. While not shown, the attachment may be controlled by an electric switch conveniently located, or by the use of a thermostat. Furthermore, the use of such 65 an attachment will prevent the burning out

of a fire-pot due to the uniform discharge of cold air thereagainst.

If desired the attachment may be used in the summer time to effect a constant change of air in a dwelling and thereby keep it cool.

What I claim is:—

1. An air circulating attachment for hot-air furnaces, comprising a head unit provided with a plurality of cool air conducting passage-ways of substantially equal area, and a plurality of conductors connected to said head unit and arranged to discharge air at different points therefrom, each conductor having communication with a distinct passage-way in said head unit and provided at their discharge ends with upwardly directed contracted vents. 75

2. An air circulating attachment for hot-air furnaces, comprising a head unit provided with a plurality of cool air conducting passage-ways of substantially equal area, a plurality of conductors connected to said head unit and arranged to discharge air at different points therefrom, each conductor having communication with a distinct passage-way in said head unit and provided at their discharge ends with upwardly directed contracted vents, and a blower arranged for connection with the receiving end 90 of said head unit and with a cool air intake pipe of a furnace. 95

3. An air circulating attachment for hot-air furnaces, comprising a head unit provided with a plurality of cool air conducting passage-ways of substantially equal area, a plurality of conductors connected to said head unit and arranged to discharge air at different points therefrom, each conductor having communication with a distinct passage-way in said head unit at one end and provided at their opposite ends with upwardly disposed contracted discharge openings extending a suitable distance on either side of the conductors, and deflecting partitions within said conductors at their discharge ends. 100

4. An air circulating attachment for hot-air furnaces, comprising a head unit provided with a plurality of cool air conducting passage-ways of substantially equal area, a plurality of conductors connected to said head unit and arranged to discharge air at different points therefrom, each conductor having communication with a distinct passage-way in said head unit at one end and provided at their opposite ends with upwardly disposed contracted discharge openings extending a suitable distance on either side of the conductors, deflecting partitions within said conductors at their discharge ends, and a blower arranged for connection with the receiving end of said head unit and with a cool air intake pipe of a furnace. 110

5. In a hot-air furnace, in combination with its fire-pot and a cool air intake pipe, of an attachment interposed in the intake pipe and between it and said fire-pot, comprising a blower, a head unit connected with the discharge side of the blower and provided with a plurality of air intake passage-ways of substantially equal area, a plurality of conductors connected to said head unit and one each in communication with a passage-way therein, the discharge ends of the

respective conductors lying substantially in the same horizontal plane next adjacent the base of said fire-pot at different points there-around, each discharge end disposed in an 15 upward direction and provided with a contracted discharge vent arranged to direct cool air in an upward direction against the wall of said fire-pot.

In witness whereof, I have hereunto 20 affixed my hand this 30th day of June, 1924.

LEON G. MYERS.
